To all whom it may concern:

Be it known that I, Julius A. Higier, a citizen
of the United States of America, residing in
Johnstown, county of Fulton, and State of New
York, have invented a new, original, and orna-
mental Design for a Glove, of which the follow-
ing is a specification, reference being had to the
accompanying drawing, forming part thereof.

Figure 1 is a rear elevational view of a glove,
showing my new design.

Figure 2 is a front elevational view of the glove
shown in Figure 1, drawn on a smaller scale.

I claim:

The ornamental design for a glove, substan-
tially as shown and described.

JULIUS A. HIGIER.
